INVENTOR
C.A.N. SHEPPARD
BY Peterston Vaughan Esq
ATTY'S

UNITED STATES PATENT OFFICE.

CHARLES ALPHA NUGENT SHEPPARD, OF OTTAWA, ONTARIO, CANADA.

ELECTRICAL VIBRATOR.

1,296,706.

specification of Letters Patent. Patented Mar. 11, 1919.

Application filed October 7, 1918. Serial No. 257,252.

To all whom it may concern:

Be it known that I, CHARLES ALPHA NUGENT SHEPPARD, a subject of the King of Great Britain, and resident of the city of Ottawa, in the Province of Ontario, Dominion of Canada, have invented certain new and useful Improvements in Electrical Vibrators, of which the following is a specification.

10 This invention relates to improvements in vibrators, and the objects of the invention are to provide an effective device constructed of few parts in which the element of noise will be practically eliminated and by which 15 a requisite amount of vibration may be efficiently transmitted to the person or patient to which it is to be applied.

Further improvement consists in the elimination of revolving parts and bearings of 20 any kind, and the consequent use of oils and lubricants, thus prolonging the effective life of the instrument.

Further objects are to generally improve 25 and simplify the construction of the device and to enable it to better perform the function required of it.

It consists essentially of the improved construction hereinafter described in detail in the accompanying specification and drawings.

In the drawings;

Figure 1 is a perspective view of the device.

Fig. 2 is a longitudinal sectional view.

35 Fig. 3 is a cross sectional view.

In the drawings, like characters of reference indicate corresponding parts in the figures.

Referring to the drawings, A represents 40 a metallic casing of suitable shape to contain the working parts and formed with a removable cover 10, normally held in position by means of screws 11 and 12 extending through the cover into suitable threaded recesses provided in the casing.

B represents a laminated core of soft iron forming a double horse shoe around the central arm 13 on which an electromagnet C is wound, the conducting wires for the electromagnet extending through a suitable perforation or opening 14 in the casing.

E represents the vibrating element comprising a pole piece 15 located immediately in front of the arm 13 of the electromagnet 50 55 C and normally supported in position and

spaced a short distance from the surface of the core by means of a spring supporting member 16 of U-shape, having its sides adjustably secured to the outer surface of the arms 17 and 18 of the core B by means of 60 screws 19 and 20 extending through slots 21 and 22 into the core.

A short sleeve or rod 25 is connected to the pole piece by a suitable screw 26 and formed in the outer end with a threaded 65 socket 27 adapted to receive a screw threaded end 28 on the contact element F, which may if desired be formed with a resilient face of rubber or the like, that illustrated being of a well known type. The sleeve or 70 rod 25 as will be seen extends through a perforation or opening 31 in the cover 10.

In using the device the electromagnet is connected to a source of alternating current 75 which will cause the pole piece to be automatically contracted and repelled, the latter being supported on the spring member 16 will produce a sufficient, yet noiseless vibration.

As many changes could be made in the 80 above construction, and many apparently widely different embodiments of my invention within the scope of the claims, constructed without departing from the spirit or scope thereof, it is intended that all matter contained in the above specification and accompanying drawings shall be interpreted as illustrative and not in a limiting sense.

What I claim as my invention is:

1. In combination, a vibrating element including a laminated horse shoe magnet, a leaf spring of substantially inverted U-shape having its extremities secured to the outer surface of the arms on the horse shoe magnet, a contact element supported by the leaf spring and electrical means for affecting the vibrating action substantially as described.

2. The device as claimed in claim 1 in which the leaf spring is adjustably secured by screws 19 and 20 extending through slots 95 21 and 22 into the core of the magnet.

3. The arrangement according to claim 1 in which a pole piece 15 is provided between the leaf spring and the core of the magnet in combination with a connecting screw 26 100 105 extending through the pole piece and connecting it with the contact element.

In witness whereof I have hereunto set my hand in the presence of two witnesses.

CHARLES ALPHA NUGENT SHEPPARD.
